UNITED STATES PATENT OFFICE.

JOHN C. MARTIN, OF SPOKANE, WASHINGTON.

WASHBOILER ATTACHMENT.

1,132,955.

Specification of Letters Patent.

Patented Mar. 23, 1915.

Application filed April 13, 1914. Serial No. 831,553.

To all whom it may concern:

Be it known that I, JOHN C. MARTIN, a citizen of the United States, residing at Spokane, in the county of Spokane and State of Washington, have invented new and useful Improvements in Washboiler Attachments, of which the following is a specification.

This invention relates to improvements in wash boiler attachments and has to do more particularly with an improved form of clothes drainer and handler.

In the most preferred embodiment of my invention the same includes a tray of open mesh work provided with handles which are arranged for engagement with the upper margin of the boiler in such a manner as to sustain the drainer therein.

The novelty of this invention relates more particularly to the handles, and one of the features consists in providing handles in sections which are hinged together, and to the tray, and which are adapted to break joint at the hinge connection of the sections.

A further feature of novelty consists in providing an improved form of hinge connection for the sections which is adapted and arranged for engagement with the boiler in a manner to suspend the strainer therein at an elevation with respect to the bottom of the boiler.

Other features of novelty will be more fully described in connection with the accompanying drawings and will be more particularly pointed out in and by the appended claim.

In the drawings;—Figure 1 is a vertical sectional view of a wash boiler illustrating therein, one form of my invention. Fig. 2 is a similar view with my improved drainer suspended at an elevation with respect to the bottom of the boiler. Fig. 3 is a plan view of my improved drainer. Fig. 4 is an edge view thereof. Fig. 5 is an end view. Fig. 6 illustrates the manner in which the clothes are dumped from the strainer into a tub.

Like characters of reference designate similar parts throughout the different figures of the drawings.

As illustrated, my improved strainer is in the form of a flat tray, indicated as a whole at 1. The tray 1 is of open mesh or reticulated structure which may comprise transversely disposed wires 2 and 3 having their ends bent about or otherwise fixed

to a margin or frame wire 4, which is bent to lend the tray its desired contour. The contour of the tray will approximate the stock form of boiler in connection with which the drainer is to be used. The margin or frame wire 4 is bent to form retaining loops 5, two being provided at each end, in the present form.

I will next describe my improved form of handle and the advantages thereof.

A handle is provided for each end of the tray, and each handle comprises a tray section, indicated as a whole at 6, and a handle section indicated as a whole at 7. The tray section 6 is formed of a single length of wire bent to approximately U-shape form, the legs 8 of which have their terminals 9 extended through the retaining loops 5, toward the tray body, and bent about the frame wire 4 to form a hinge connection. At all times, the legs 8 will be disposed outwardly with respect to the retaining loops 5 so as to prevent the legs 8 from being tilted or swung over and upon the tray, the retaining loops 5 functioning to arrest inward movement of the legs from a vertical position. The bight of the U-shaped tray section 6 is bent to form loops 10, in spaced relation with respect to each other, which loops project outwardly from the legs 8, as indicated at 11, for engagement with the end upper margin 12, of the boiler 13, as clearly shown in Fig. 2. The remainder of the bight of each tray section extends across the legs 8, as indicated at 14, outwardly over the legs 8 so as to stiffen the loops 10 against distortion.

Each handle section is composed of a single length of wire which is shown twisted upon itself to form a stiffened stem 15, the wire ends being forked as indicated at 16, and having their terminals eyed to loop through the supporting loops 10 as indicated at 17. The forked ends 16 are bent at an obtuse angle to the stem 15, as shown more particularly in Fig. 4. The foregoing construction provides for a hinged connection between the handle and tray sections, 7 and 6, respectively. The outer end of the handle sections are spread, as indicated at 18, to form triangular handle loops on which wooden handles 19 may be revolvably mounted. By reference more particularly to Fig. 4, it will be seen that the handle ends or loops are bent outwardly with respect to the stems 15, for a purpose which will presently appear.

Fig. 1 shows the device in the position it would assume when the clothes are being boiled. Even with relatively long handles no difficulty is experienced in using the device of my invention in connection with a relatively shallow boiler, and closing the lid thereof, because of the fact that the handles are made in sections which are hinged to break joint. Furthermore, relatively long handles can be provided thereby protecting the user against being burned, when handling the clothes. The bent handle terminals project upwardly and are held out of contact with the clothes when the handle sections are disposed upon the clothes, as shown in Fig. 1. When it is desired to drain the clothes, the handles will be grasped and the tray will be lifted to the position shown in Fig. 2 so as to dispose the hinged portions of the handle sections in supported engagement with the upper margin of the boiler thereby extending the clothes above the water level. In order to further facilitate and hasten the draining operation, downward pressure may be exerted upon the upwardly extending handles 19 so as to press the water out of the clothes. Even in this operation the hands of the user need not be exposed to burning contact with the clothes. In dumping the clothes from the tray into a rinsing receptacle or tub 20, the thumbs can be hooked into the projecting handles so

as to spread the same, as clearly indicated in Fig. 6.

It is believed that the novelty and utility 35 of my invention will be fully understood from the foregoing description, and while I have herein shown and described one specific form of my invention, I do not wish to be limited thereto except for such limitations 40 as the claim may import.

I claim:—

A clothes supporting and draining attachment for wash boilers, comprising a draining clothes tray holder, tray handle 45 sections of substantially U-shaped form having their free ends hinged to said tray holder and having their bights bent to form outwardly projecting supporting loops in spaced relation with respect to each other for 50 engagement with the boiler to support the tray therein, and a handle section hinged to each tray section at the supporting loops thereof to permit the handles to break joint between their ends, substantially as de- 55 scribed.

In testimony that I claim the foregoing as my own, I hereby affix my signature in the presence of two subscribing witnesses.

JOHN C. MARTIN.
